CLAIM

The ornamental design for an electronic sound generator, as shown and described.

DESCRIPTION

FIG. 1 is a perspective view of a electronic sound generator showing my new design, with the broken lines shown for illustrative purpose only and forming no part of the claimed design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof.

FIG. 1

FIG. 2

FIG. 3

FIG. 4**FIG. 5****FIG. 6****FIG. 7**
